UNITED STATES PATENT OFFICE.

CLAUDIUS DORNIER, OF FRIEDRICHSHAFEN, GERMANY, ASSIGNOR TO THE FIRM:
ZEPPELINWERK LINDAU GESELLSCHAFT MIT BESCHRANKTER HAFTUNG, OF
LINDAU-REUTIN, GERMANY.

FLYING BOAT.

Application filed June 15, 1921, Serial No. 477,843, and in Germany November 14, 1917.

(GRANTED UNDER THE PROVISIONS OF THE ACT OF MARCH 3, 1921, 41 STAT. L., 1313.)

My invention refers to flying boats and more particularly to means for increasing the transverse stability of the boat while it rests on the water. In order to avoid fitting 5 the boat with outriggers or enlarging the hull of the boat, whereby its weight would be increased, thin bearing planes extending substantially at right angles to the center plane of the boat have been fitted to the 10 hull. However, as these planes are mounted on the hull far above the water line, the transverse stability is not increased at slight 15 inclinations of the boat. At larger inclinations, however, the outer portions of the bearing plane come in contact with the water first, while the space intermediate the bearing plane and the hull remains unsupported. In consequence thereof, the submerged area 20 is increased in jerks which may easily cause serious damage.

According to the present invention, now, these drawbacks are overcome by the arrangement of short self-supporting fin-shaped floats attached to the side walls of 25 the hull and the sectional height of which decreases steadily towards their outer edges. It is essential that their upwardly extending lower surfaces meet the hull of the boat approximately in the water line, for in this case the submerged surface will increase rapidly 30 on the dipping side even with a slight tilt sideways. In this manner the transverse stability is favorably increased.

Depending upon the purpose and the peculiarity of the flying machine, a greater or lesser dipping depth of the root of the wing with the flying machine resting horizontally 35 on the water may be of advantage.

With a very narrow boat a fin dipping 40 into the water up to the root offers special advantages because this arrangement renders it possible to build the hull extraordinarily narrow, thus effecting a considerable saving in weight and air resistance. The 45 fins designed according to the present invention are particularly suitable for facilitating starting and landing. In starting the high hydrodynamic efficiency brought about by the favourable side proportions of the 50 floating body constituted by the hull and the fins, is particularly noticeable. In this manner a materially increased buoyancy is attained with the same water resistance.

With increasing travelling speed and growing lifting power of the fins as also of the 55 supporting plane the area of water resistance decreases rapidly. At the moment of rising from the surface of the water the latter only touches the very narrow hull, whereby the release is effected with extraordinary ease. 60 The decrease of the floating stability with increasing speed is no disadvantage as with increasing speed disturbances of the lateral stability may be equalized by the transverse 65 rudder.

When landing on the water, only the very narrow hull dips first and for this reason the shock in landing is very small. As the speed is reduced, the water resistance at first increases very gradually, but more rapidly 70 when the fin dips into the water. In this way an extremely soft braking of the travel of the machine is attained.

By employing fins shaped as above described the floating stability is very much 75 improved without increasing the span of the fins. Hitherto, in order to avoid increasing the width of the hull, the extreme ends of the supporting surfaces were provided with floats for increasing the transverse stability. 80 This arrangement, however, involves considerable disadvantages as compared with the arrangement according to the present invention as it increases the weight and resistance. With supporting planes placed high up and 85 floats laterally attached to these planes the list of the flying boat will be considerable before the float begins to act; and with low supporting surfaces, in a heavy sea, the waves will wash over the supporting surfaces and knock up against them, which for 90 reasons of safety and stability must be avoided under any circumstances.

Moreover, in case some object floating on 95 the water should strike a side float attached to the supporting surfaces, the wing or at least the frame work of the float are endangered because, in consideration of the weight involved, a float attached to a supporting surface can never attain the strength of a 100 fin forming part of the hull.

The outward shape of the fins constructed in accordance with this present invention may vary. For instance: the fins may be 105 designed in such manner that with increasing inclination of the flying machine they

gradually dip more from the root onward. In some cases it may be preferable to make the fin of such a shape that the outside portion dips first. Moreover, the flying boat 5 designed in accordance with the present invention is particularly well suited for fitting starting or transporting wheels. Such wheels are known to have been fitted to hydroplanes before, but there are difficulties 10 encountered with flying boats with narrow hulls inasmuch as only by the use of chassis with large lateral overhang it becomes possible to attain sufficient transverse stability. With a flying boat designed in accordance 15 with the present invention the amphibious arrangement is attained in an extremely simple manner by avoiding the disadvantages above referred to and without material increase in weight, by the wheels being fitted 20 to the above described fins which may be built strong enough to take up the shocks during landing. Even if landing on the ground is not intended, wheels fitted to the fins may prove of great advantage for 25 launching and beaching the machine.

In the drawings affixed to this specification and forming part thereof different forms of flying boats embodying my invention are illustrated diagrammatically by 30 way of example. In the drawings—

Figs. 1 to 3 are a rear view, plan view and side elevation, respectively, of the hull of a flying boat, and

Fig. 4 is a partial front elevation of the 35 flying boat as a whole.

Referring to the drawings, the hull A is provided with two steps a^1 and a^2 . To each side of the hull A a fin-shaped float B is attached. E is the supporting plane. 40 The dotted lines b^1 represent ribs which indicate the peculiar form of these fins. This shape has been chosen in order to reduce the air resistance to a minimum during the flight; moreover, in case of lateral in-

clinations of the floating air craft a vigorous righting moment is obtained by the fin-shaped floats even in case of a slight list. 45

I wish it to be understood that I do not desire to be limited to the exact details of construction shown and described, for obvious 50 modifications will occur to a person skilled in the art.

I claim:

1. In a flying boat in combination, a hull, a supporting plane and a pair of short self-supporting fin-shaped floats attached to said hull, the sectional height of said floats decreasing steadily towards their outer ends and their upwardly extending lower faces meeting the hull substantially in the water line so as to be clear of the water, when the hull is in normal position. 55

2. In a flying boat in combination, a hull, a supporting plane and a pair of short self-supporting fin-shaped floats of stream-lined section attached to the side walls of said hull, the sectional height of said floats decreasing steadily towards their outer ends, their upwardly extending lower faces meeting the hull substantially in the water line so as to be clear of the water, when the hull is in normal position and being slightly inclined downwards from fore to aft. 65

3. In a flying boat in combination, a hull, a supporting plane and a pair of short self-supporting fin-shaped floats of stream-lined section attached to the side walls of said hull with their upper surfaces substantially at a level with the upper edges of said hull, the sectional height of said floats decreasing steadily towards their outer ends, their upwardly extending lower faces meeting the hull substantially in the water line so as to be clear of the water, when the hull is in normal position and being slightly inclined 70 downwards from fore to aft. 80

In testimony whereof I affix my signature.
CLAUDIUS DÖRNIER.
